CONTAINER

John F. Peters, Leonia, N. J., assignor to American Can Company, New York, N. Y., a corporation of New Jersey

Application June 2, 1936, Serial No. 83,171

2 Claims. (Cl. 220—39)

The present invention relates to a sheet metal container or can having a removable flanged cover which is applied by a turning movement, the cover flange and can being provided with co-
5 operating interrupted thread sections for securing the applied cover in can closing position, and has particular reference to such a can which has a reinforced necked-in or reduced diameter end over which the cover may be applied so that 10 the exterior surface of its flange will be flush with the outside of the can.

An object of the invention is the provision of a can adapted to be closed with a frangible seal and a flanged reclosure cover wherein the can 15 is formed with a plurality of groups of vertical corrugations which are spaced around the circumference of the can adjacent its top end for reinforcing and for reducing or necking in this end of the can so that the exterior surface of the 20 flanged cover will be flush with the outside of the can when the cover is applied.

Another object is the provision of such a can wherein the groups of vertical corrugations are separated by uncorrugated portions of its reduced diameter, these uncorrugated portions providing smooth surfaced walls in which interrupted 25 thread sections are formed which cooperate with similar thread sections formed in the cover for locking the latter in can closing position.

30 The groups of corrugations are so arranged that they are intermediate of the thread sections of the body so that the upper part of the can body is very much stiffened and the thread sections have their full effect in drawing down the 35 reclosure cover tightly upon the mouth of the can.

Still another object is the provision of a can of this character having a corrugated necked-in end formed in a manner to improve the appearance of the can and to greatly enhance its 40 commercial value.

Numerous other objects and advantages of the invention will be apparent as it is better understood from the following description, which, taken 45 in connection with the accompanying drawing, discloses a preferred embodiment thereof.

Referring to the drawing:

Figure 1 is a perspective view of a closed and sealed can embodying the instant invention; 50 Figure 2 is an enlarged fragmentary plan view of the can shown in Fig. 1 with parts broken away;

Figure 3 is an enlarged fragmentary elevation of the upper end of the can, with parts broken 55 away;

Figure 4 is an enlarged fragmentary section of the upper portion of a can body before necking in and from which the can shown in Fig. 1 is produced;

Figure 5 is a view similar to Fig. 4 and illustrating the can body after its upper end has been necked in; and

Figure 6 is an enlarged fragmentary section of the upper end of the can shown assembled with its cover, the section being taken substantially 10 along the line 6—6 in Figure 1.

A preferred embodiment of the invention as disclosed in the drawing comprises a cylindrical sheet metal can body 11 closed at its bottom end with a closure member which is secured to the 15 body in a suitable seam 12. The upper end of the body wall is strengthened by an annular inwardly bent bead 14 (Figs. 4, 5 and 6).

Above the bead 14 the body wall 11 is reduced in diameter or necked-in as at 15 (Fig. 5), the material of the body wall being bent into groups of vertical corrugations 16. The groups of corrugations are spaced at intervals around the circumference of the body and are separated by uncorrugated portions 17. This grouping adds 25 materially to the strength of the upper end of the body and at the same time presents a pleasing appearance.

The reduction of the body wall in this manner produces in effect a second annular strengthening bead 18 which is disposed above and adjacent the bead 14. The bead 18 curves outwardly, merging into the bead 14 having a cross section as in an S-curve, but does not project beyond the body wall. 30

The top of the body wall 11 is preferably bent inwardly to provide a curled edge 21 which forms a smooth mouth for the open end of the can and further reinforces or strengthens this part of the body. This curled edge is utilized to hold in 40 place a frangible seal 22 which closes off the open end of the can.

A cover 25 is applied to the can over the top of the frangible seal 22 and may be used as a reclosure cover after the frangible seal has been broken 45 out. The cover is formed with a top wall 26 and a depending side wall or flange 27 which extends down adjacent the necked-in portion 15 of the body wall 11 with its exterior surface flush with the outside of the body.

Threaded elements are formed in both can and cover and these elements cooperate to draw the cover top wall 26 into tight engagement with the top of the curled body edge 21 when the cover is applied to the can. These threaded elements in- 55

clude a plurality of spaced interrupted thread sections 28 (Fig. 3) which are struck inwardly from the cover flange 27 and which are disposed at an angle to the horizontal. Cooperating outwardly struck interrupted thread sections 29 are formed in the uncorrugated necked-in sections 17 of the body wall and these thread sections are also disposed at an angle to correspond with the cover thread sections. The thread sections in can and cover flange are relatively short so that the thread sections of the cover may pass directly between the thread sections of the body when the cover is first applied.

A depending projection 31 formed at one end of each of the thread sections 29 provides a locking lug which holds the engaged threads in interlocked position as shown in Fig. 3 this being after the cover has been applied to the can and has been rotated into locked position. This general form of threaded connection is often used in sheet metal cans for securing can and cover together.

Rotation of the cover is facilitated by a suitable knurling 32 formed in the cover flange wall 27. This knurling permits a more secure grip on the cover when it is being rotated into closed position or removed therefrom.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A can comprising a body having an open upper end, the portion of said body adjacent its

upper end being of reduced diameter to provide a necked-in closure receiving seat, said seat comprising a plurality of peripherally spaced substantially smooth areas with interrupted thread sections formed therein and vertically corrugated intermediate areas, said corrugations providing reinforcement for the open end of the can and including excess metal incident to the reduction in diameter of said necked-in portion, and a closure having a flange provided with interrupted thread sections which cooperate with the thread sections of said body to removably lock the closure in place, the exterior of said closure flange being substantially flush with the body wall when the closure is in locked position on the can. 15

2. A can comprising a body having an open upper end surrounded by an inwardly disposed curled edge, the portion of said body adjacent its upper end being of reduced diameter to provide a necked-in closure receiving seat, said seat comprising a plurality of peripherally spaced substantially smooth areas with interrupted thread sections formed therein and vertically corrugated intermediate areas, said corrugations providing reinforcement for the open end of the can and including excess metal incident to the reduction in diameter of said necked-in portion, a closure having a flange provided with interrupted thread sections which cooperate with the thread sections of said body to removably lock the closure in place, the exterior of said closure flange being substantially flush with the body wall when the closure is in locked position on the can, and a frangible seal disposed across the open end of said body to protect the contents of the container, the peripheral portion of said seal being secured within said inwardly curled edge of said body. 20 25 30 35
